SHEET FEEDER.

Application filed August 11, 1927. Serial No. 212,204.

Our invention relates generally to improved sheet-feeders used for automatically separating and forwarding successive sheets of paper or other impression-receiving material to printing, folding or ruling machines, or to such other types of machines as are devised to operate thereafter on such sheets.

The objects of our invention are, among other things, mainly to provide a sheet-feeder 10 of this character having a simplified design and embodying therein separate mechanisms capable of performing rapid and efficient work in separating sheets of different sizes as well as of varying thicknesses and grades, and 15 such mechanisms also being very sensitive in action under different conditions of sheet-separation, yet they are not likely to get out of order, and may be readily shifted and adjusted for different runs by the operator. 20 These devices are preferably incorporated in a feeder of the "continuous" type in which the sheets are separated and advanced from the front top portion of a fanned-out bank of paper on the feed-board.

25 With these aims in view we have devised a front-edge feeder having a novel and improved suction feeding-off device which is usually arranged in pairs across the feeder, the operation of each device being controlled 30 by a separate cut-out finger located between the usual feed-rolls and actuated by the sheet advanced to limit the forward movement of the suction feeding-off device while the shutting off of the suction from such device 35 promptly to release the advancing sheet when seized by the feed-rolls as well as the application of the suction to pick up the sheet is timed in regular succession in each cycle of the feeder.

40 A further feature is to embody in such a feeder an intermittently rotatable suction feed-wheel which will be automatically raised and lowered in each cycle to pick up and feed off the successive sheets, with novel mechanisms to control the timing and extent of the 45 rotary movement of the wheel so that the front margin of the top sheet is seized by the wheel while at rest and during its lowering movement, and immediately thereafter such wheel is lifted and begins its sheet-forwarding rotary movement.

A further feature of our invention is to

provide a novel mechanism in conjunction with the intermittently rotatable suction feed-wheel whereby the leading edge of the 55 top sheet after it is seized by the feed-wheel will be retracted slightly or moved rearwardly before such wheel is revolved forwardly to advance such top sheet. Such rearward movement of the top sheet advantageously 60 frees the front margin of such sheet before its forward movement to the feed-rolls.

Our improved sheet-feeder also embodies other advantageous features of novelty and improvement in which the various operating 65 members are greatly simplified in form, arrangement and interaction, in the performance of their intended functions under varying conditions of usage with different kinds of paper stock, all of which will be herein-after described and then particularly pointed out in the appended claims.

The accompanying drawings show our improvements in their preferred embodiment in a continuous sheet-feeder; such improvements, however, are not to be restricted to any particular type of sheet-feeder, as these features of invention may be incorporated in various forms of feeders with similar advantages and results.

Of the drawings, Fig. 1 is an end elevation of our feeder looking rearwardly and illustrating the general arrangement of the various parts and mechanisms embodied therein;

Fig. 2 is a section taken on the line 2—2 of Fig. 1 showing the driving gears for the cam-shaft and mechanism for actuating the feed-wheel shaft;

Fig. 3 is a detail section taken on the line 90 3—3 of Fig. 1;

Fig. 4 is a section taken on the line 4—4 of Fig. 1 showing the suction feed-wheel and also the trip finger in lowered position;

Fig. 5 is a section taken on the line 5—5 of Fig. 1 showing the latch for the trip finger;

Fig. 6 is a view similar to Fig. 5 showing the latch disengaged when the trip finger is moved outwardly by the advanced top sheet;

Fig. 7 is a section taken on the line 7—7 of Fig. 1 showing the mechanism for controlling the suction on the feed-wheel;

Fig. 8 is a view similar to Fig. 6 showing the mechanism for lifting and holding the

trip finger up from the path of the top sheet;

Fig. 9 is a detail section showing means for resetting the trip-latch; and

Fig. 10 is an enlarged detail section of the 5 lower rim of the feed-wheel showing its movement in diagrammatic form when slightly retracting the top sheet before rotating to advance same to the feed-rolls.

Similar numerals refer to similar parts 10 throughout the several figures.

Referring to the drawings, the side-frames 11 and 12 of the feeder are suitably supported on standards (not shown), and suitably secured between the side-frames 11 and 12 is the 15 feed-board 13 over which travel a series of feed-belts 14 to advance the fanned-out bank of sheets 15 along the feed-board 13. The belts 14 (only one being shown in Fig. 2) pass 20 forwardly around the drum 16 mounted on the cross-shaft 17 journalled in suitable bearings in the side-frames 11 and 12. The shaft 17 is actuated in the usual manner so that the 25 belts 14 are intermittently advanced to carry the bank of fanned-out sheets 15 to the sheet separating and feeding devices arranged across the front edge of the feed-board 13 as shown in Figs. 4 and 5.

In the present embodiment of our feeder, 30 the sheet separating and forwarding devices are duplicated on either side of the machine and are adjustable laterally in the machine to accommodate for sheets of different sizes; hence a description of one set of such devices will be sufficient, since both sets are built and 35 operate in a similar manner. The main cam-shaft 18 extends across the feeder and is suitably supported in bearings in the side-frames 11 and 12 as shown in Fig. 1. This shaft 18 is driven in a counter clockwise direction 40 (Fig. 2) to make a complete revolution in each cycle of the feeder by the gear 19 secured thereto, which gear 19 engages the pinion 20 mounted on the stub-shaft 21 secured in the side-frame 11; the pinion 20 meshes with the 45 gear 22 affixed to the stub-shaft 23 on which is mounted the gear 24 engaging the idler gear 25 which is driven by another idler gear 26 which engages the gear 27 affixed to the main power shaft 28 suitably journalled in the 50 side-frames 11 and 12 (the various arrows in Fig. 2 showing the directions of rotation of the several gears and pinions). The power shaft 28 is driven in a clockwise direction 55 (Fig. 2) by the chain 29 passing around the sprocket 30 affixed to the shaft 28, the chain 29 being actuated from any suitable source of power.

Extending across the feeder between the side-frames 11 and 12 is the tie-shaft 31 and 60 also the cross suction tube 32 on which are rotatably secured the rock-arms 33 and 34 in the forward ends of which rock-arms are journalled the outer ends of the feed-wheel shaft 35 (Fig. 1). Mounted on the shaft

35 are the suction feed-wheels 36 (two being 65 shown in Fig. 1), the rim 37 of each wheel having spaced-apart perforations 38 preferably arranged in staggered relation as shown in Fig. 1; the suction shoe 39 with its nozzle 40 rides along the inner face of the rim 37 70 (Figs. 4, 5 and 10), and is held in position on the end of the hollow arm 41 journalled on, and connected to, the cross suction tube 32. The nozzle 40 registers intermittently with the successive perforations 38 in the rotary 75 feed-wheels 36 as the latter are revolved in a counter-clockwise direction (Figs 4 and 5). The required suction to operate the feed-wheels 36 is applied to the tube 32 from the passage 42 in the side-frame 12, such suction 80 being derived from any suitable air-exhausting devices (not shown). The forward portion of the top sheet taken from the bank 15 adheres to the exterior surface of the rim 37 opposite the nozzle 40 (Fig. 10), and is separated and advanced to the bite of the usual 85 lower feed-roll 43 and upper drop-roll 44 by the feed-wheels 36.

The feed-roll 43 is affixed to the main power shaft 28 (Figs. 1 and 4), while the drop-roll 44 is journalled in the rock-arm 45 which is raised and lowered in the usual manner to seize and convey forwardly the advancing top sheet when its leading edge has passed over the lower guide-plates 46 mounted on 90 the cross-rod 47 into the bite of the feed-rolls 43 and 44 (Figs. 4 and 5). The front edges of the upper sheets comprising the front portion of the bank 15 are loosened and kept agitated by a blast of air from the nozzle 48 95 mounted on the pipe 49 (Figs. 4, 5 and 10) connected with any suitable air pump not shown.

Means are provided to impart an intermittent rotative movement in one direction 105 to the feed-wheels in each cycle of the feeder, which rotations are varied in extent and are determined and controlled by the position of the leading edge of the advancing top sheet when brought into the bite of the feed-roll 110 43 and drop-roll 44. In the present embodiment the feed-wheel 36 is affixed to the hub 50 sleeved on the shaft 35, the hub 50 carrying the circular ratchet plate 51 which coacts with the circular plate 52 mounted on the hub 53 secured to the shaft 35. The plate 52 carries on its face the leather disk 54 which normally bears against the plate 51 to actuate the feed-wheel 36 (Fig. 1). The spring 55 coiled about the shaft 35 between the hub 115 50 and adjustable collar 56 forces the ratchet plate 51 into coacting engagement with the plate 52 and disk 54 so that normally the feed-wheel 36 revolves with the shaft 35.

Means are provided to impart to the shaft 120 35 an intermittent, rotative, movement of predetermined length and only in one direction in each cycle of the machine which are

best shown in Figs. 1, 2 and 3. The cam 57 affixed to the cam-shaft 18 engages the cam-roller 58 pinned to the slotted end 59 of the rod 60 pinned to the rock-arm 61 secured to the stub-shaft 62 mounted in the side-frame 11. Also secured to the shaft 62 is the rock-arm 63 to which is pivoted the horizontal rack-bar 64 which engages the gear 65 sleeved on the shaft 35. Pinned to the gear 65 is the rock-arm 66 carrying the pawl 67 which is kept by the spring 68 in operative engagement with the ratchet 69 affixed to the shaft 35 as shown in Fig. 3. The pull spring 70 secured to the rock-arm 63 (Fig. 2) keeps the cam-roller 58 always in engagement with the cam 57. By this mechanism the rack-bar 64 is regularly reciprocated in each revolution of the cam 57 whereby a predetermined rotative movement in one direction only is imparted to the shaft 35 and feed-wheel 36 in each cycle of the machine.

Means are also provided to raise and lower the suction feed-wheel 36 during each cycle to accommodate for banks of sheets of stock having different thicknesses and textures, combined with novel means whereby the front edge of each top sheet picked up by the feed-wheel 36 may be slightly retracted over the subjacent sheets when first seized by the feed-wheel. In the present embodiment shown in Figs. 1, 2, 5 and 10, the cam-shaft 18 has secured thereto the collar 71 to which is affixed the cam 72. Pivoted to the rock-arm 34 is the vertically-disposed strap 73 having the slot 74 formed therein enclosing the cam-shaft 18 as shown in Fig. 5. The upper end of the strap 73 carries the cam-roller 75 which rides on the cam 72 and is held in engagement therewith by the weight of the rock-arm 34 and associated devices.

Suction is applied to the feed-wheels 36 and shut off therefrom in regular succession in each cycle through the continued movement of the feeder by means of the cam 76 mounted on the end of the cam-shaft 18 outside the side-frame 12 which cam 76 engages the roller 77 (Fig. 7) pinned to the upper arm 78 of the rock-lever 79 pivoted on the stub-shaft 80 affixed to the side-frame 12. The lower arm 81 of the rock-lever 79 carries the valves 82 which coact with the ports 83 connected with the passage 42 to make and break the suction in the well-known manner. The cams 72 and 76 are so set in timed relation with each other that when the feed-wheel 36 is being lowered in a state of rest the suction will then be applied to pick up the front margin of the top sheet (Figs. 2 and 10); then when the feed-wheel 36 is further lowered such wheel will swing rearwardly in its orbit in the direction of the arrow (Fig. 10) and so slightly retract the front margin to free the front edge of this loosened top sheet from the subjacent sheets. Thereafter the

feed-wheel 36 is raised and rotated forwardly to separate the top sheet and advance same to the cut-out finger or trip in the bite or the rolls 43 and 44, after which the ports 83 are opened to atmosphere to cause the feed-wheels to release the top sheet.

Means are provided to stop or interrupt the forward rotative movement of the feed-wheels in any part of the cycle immediately upon the lifting of a cut-out finger or trip actuated by the advancing sheet which means may be widely varied in structure and operation.

In the present embodiment the bracket 84 affixed to the tie-shaft 31 is forked at its lower end into which fork is fixed the cross-pin 85 on which is adjustably fastened the collar 86 on which is pivoted the cut-out finger or trip 87, the lower forward end depending in the slot 88 formed in the lower guide-plate 46 and movable in the slot 88 forwardly from and beyond bracket 84 as shown in

Figs. 1 and 4-6. Threaded through the lug 91 formed from the collar 86 is the adjusting cap-screw 92 with its cap 93 bearing on the under side of the trip-finger 87 whereby the position of the trip-finger 87 relatively to the feed-rolls 43 and 44 may be shifted either to advance or retard the timing of the interruption or stopping of the forward rotative movement of the feed-wheels 36. Also adjustably secured to the cross-pin 85 is the

collar 94 (Figs. 5 and 6), carrying the latch-arm 95 with its beveled faced hook 96 to coact with the beveled latch lug 97 projecting laterally from the arm 98 of the bell-crank lever 99 mounted on the stub-shaft 100 secured in

the bracket 84. The upper arm 101 of the lever 99 carries the cam-roller 102 which rides on the cam 103 secured to the cam-shaft 18. The coil-spring 104 between the bracket 84 and the arm 98 normally keeps the latch members 96 and 97 in engagement (Fig. 5) with the trip-finger 87 lowered in operative position in the slot 88. Secured to the arm 98 is the catch-pawl 105 arranged to move into and out of engagement with the ratchet plate 51 which drives the feed-wheel 36, Figs. 4 and

5 showing the pawl 105 out of engagement with the plate 51 while Fig. 6 shows these parts in locked position after the trip-finger 87 has been moved by the advanced sheet.

Referring to Fig. 6, when the finger 87 is moved from its dotted line position to the full line position by the advanced top sheet as indicated by the arrow in Fig. 4, the latch hook 96 is dislodged from its engagement with the latch lug 97, and the arm 98 under the tension of the spring 104 is pulled to the left thereby bringing the pawl 105 into locking engagement with the teeth of the ratchet plate 51 which instantly stops the rotative movement of the feed-wheels 36. The latch lug 97 will be reset over the hook 96 when the high part of the cam 103 engaging the roller

115

120

125

102 at the end of the cycle forces the bell-crank lever 99 to the right, all as shown in Fig. 9, since the cam 103 makes a complete revolution in each cycle of the feed-wheel 36 as hereinbefore explained.

We have also provided novel devices to lift and then hold the trip-finger 87 in its raised position off the body of the sheet after the latter is seized and is being forwarded by the feed-rolls 43 and 44: Referring to Figs. 4, 5, 6 and 8 the bracket 84 carries the stub-shaft 106 on which is pivoted the rock-lever 107 the upper arm 108 carrying the cam-roller 109 which engages the cam 110 affixed to the cam-shaft 18. The lower arm 111 has the adjustable screw-bolt 112 threaded through its lower end the tip 113 of the bolt 112 normally being out of engagement with the trip-finger 87 (Fig. 4) while the cam-roller 109 is riding on the high part of the cam 110. The cam 110 is so timed with the cam 103 and the outward movement of the trip-finger 87 (Fig. 6), that as soon as the front portion of the top sheet is seized in the bite of the feed-rolls 43 and 44 (Fig. 8), the roller 109 rides down into the dwell of the cam 110 by the action of the pull spring 114 pinned between the bracket 84 and the arm 108 which causes the arm 111 to swing upwardly (Fig. 8) to raise the trip-finger 87 from its dotted to its full line position and against the tension of the light spring 115 pinned between the arm 111 and the bracket 84. The force of the pull spring 114 is of sufficient strength to overcome the spring 115 and always cause the cam-roller 109 to follow the cam 110. By this device the trip finger 87 is positively held in its lifted position until the tail end of the top sheet has passed through the feed-rolls 43 and 44, and the resetting mechanisms have been actuated by the cam 103 to bring the parts into the positions shown in Figs. 4 and 5, the spring 116 pinned between the bracket 84 and the arm 117 projecting from the lug 91 aiding in restoring the trip-finger to its full line position shown in Fig. 4.

The operation of our sheet-feeder is substantially as follows: When the feed-wheels 36 are being lowered in a state of rest during the idle stroke of the rack-bar 64, the suction is applied to the nozzle 40 and the top sheet is picked up as shown in Fig. 4; then as the feed-wheels 36 are further lowered they are swung rearwardly about the suction tube 32 as a center as shown in Fig. 10 whereby the front edge of the picked-up top sheet is slightly retracted to free its front edge from the subjacent sheets which separation is aided by the air blast from the nozzle 48. Then the wheels 36 are raised and begin their rotative movements by the mechanism hereinbefore described and shown particularly in Figs. 4, 5, 6 and 8. As soon as the leading edge of the top sheet has been advanced by

the revolving feed-wheels 36 so that such sheet lifts the trip-finger 87 as shown in Fig. 6 with the sheet in position to be seized by the feed-rolls 43 and 44, the latch hook 96 is drawn away from the latch lug 97 which disengagement immediately snaps the bell-crank lever 99 in a clockwise direction by the pull of the spring 104 thereby throwing the pawl 105 into engagement with the ratchet plate 51 to interrupt or stop the rotative movements of the feed-wheels 36. By this mechanism the separate trip fingers 87 actuated by the leading edge of the top sheet directly control the extent of the rotative movements of the feed-wheels. As soon as the latch members 96 and 97 are disengaged, the mechanism for lifting the trip-finger 87 comes into operation as shown in Fig. 8 with the cam-roller 109 riding off the high part of the cam 110 whereby the arm 111 is raised so that the bolt 112 will lift and hold the trip-finger off the body of the sheet seized by the feed-rolls (Fig. 8). Meanwhile the cam 76 has acted to open the ports 83 thereby shutting off the suction from the feed-wheels 36 and releasing the sheet now under the control of the feed-rolls. As the tail end of the sheet is passing through the feed-rolls 43 and 44, the roller 102 will ride up on the high part of the cam 103 (Fig. 9) which will swing the arm 98 to the right thereby disengaging the pawl 105 from the ratchet plate 51 and also simultaneously resetting the latch lug 97 in locking engagement with the latch hook 96 with the trip-finger restored to its Fig. 4 position and the feed-wheels 36 free to begin their rotations in conjunction with the shaft 35 in the succeeding cycle of operations.

The foregoing constructions embody the essential features and principles of our invention as embodied preferably in a continuous sheet-feeder which will have a wide range of "flexibility" through the sheet control of the extent of the forward movements of the intermittently rotating suction feed-wheels, combined with means to synchronize the raising and lowering of such feed-wheels in each cycle, the final lowering movement of the wheels slightly retracting the front edge of the top sheet already seized by the feed-wheels whereby such sheet is advantageously freed from the other sheets in the bank before its forward movement. In short the sheet-actuated trip-fingers directly cause the stopping of the forward feed of the suction wheels determined by the position of the sheet as it is about to be seized and forwarded by the feed rolls.

Various changes may be made in the structural details of our feeder without departing from the scope of our improvements or sacrificing its chief advantages. However, the foregoing is sufficient to disclose the underlying principles and features of the inven-

tion as particularly applied to a continuous sheet feeder.

We claim as our invention:

1. In a sheet-feeder, a suction feed-member rotatable in one direction for separating and advancing sheets forwardly from a pile and sheet-controlled means for varying the extent of the rotary movement of said member. 5
  2. In a sheet-feeder, a suction feed-member intermittently rotatable only in one direction for separating and advancing the successive sheets and sheet-controlled means to vary the extent of the rotary movement of said member in each cycle. 10
  3. In a sheet-feeder, a suction feed-member for advancing successive sheets, means to rotate said member in one direction only, and sheet-controlled means to variably stop the rotary movement of said member. 15
  4. In a sheet-feeder, a suction feed-member for advancing successive sheets, means for imparting an intermittent rotary movement to said member in one direction only in each cycle, and sheet-controlled means to variably stop said intermittent rotary movement of said member. 20
  5. In a sheet-feeder, a suction feed-member rotatable in one direction for separating and advancing the successive sheets and sheet-controlled means for interrupting the rotary movement of said member in any part of the cycle. 25
  6. In a sheet-feeder, a suction feed-member intermittently rotatable in one direction only for separating and advancing the successive sheets and means controlled by the advanced sheet for interrupting said intermittent rotary movement of said member in any part 30 of the cycle.
  7. In a sheet-feeder, a suction feed-member intermittently rotatable only in one direction for separating and advancing the successive sheets and means controlled by the advanced sheet for interrupting the rotary movement of said member in any part of the cycle. 35
  8. In a sheet-feeder, a suction feed-member rotatable in one direction for separating and advancing sheets forwardly from a pile, means for lowering and raising said member to and from said pile, and sheet-controlled means for varying the extent of the rotary movement of said member. 40
  9. In a sheet-feeder, a suction feed-member intermittently rotatable for advancing successive sheets from a pile, means to lower said member to said pile while at rest to pick up a sheet, means for raising said member and rotating same to advance the sheet, and means controlled by the advanced sheet to interrupt the sheet-forwarding rotary movement of said member in any part of the cycle. 45
  10. In a sheet-feeder, a suction feed-member intermittently rotatable only in one direction for advancing successive sheets. 50
- from a pile, means to lower said member to said pile while at rest to pick up a sheet, means for raising said member and rotating same, and means controlled by the advanced sheet to interrupt the rotary movement of said member in any part of the cycle. 55
11. In a sheet-feeder, a rotatable suction feed-member for separating and advancing successive sheets forwardly from a fanned-out bank, means for lowering and raising said member to and from said bank while at rest to pick up a sheet, means to rotate said member when raised from the bank, and sheet-controlled means to variably stop the rotary movement of said member. 60
  12. In a sheet-feeder, a rotatable suction feed-member for separating and advancing successive sheets forwardly from a fanned-out bank, means for lowering and raising said member to and from said bank while at rest to pick up a sheet, means for imparting a predetermined rotary movement to said member in one direction only in each cycle when raised from the bank, and sheet-controlled means to variably stop the rotary movement of said member. 65
  13. In a sheet-feeder, a suction feed-member intermittently rotatable in one direction only to advance the sheets, means controlled by the advanced sheet to vary the extent of the said intermittent rotary movement of said member, and means to vary the timing of said last-mentioned means. 70
  14. In a sheet-feeder, a suction feed-member intermittently rotatable in one direction only to advance the sheets, means for applying suction to said member in timed relation with its rotary movements, a cut-out finger actuated by the advanced sheet to interrupt said intermittent rotary movement of said member, and means to adjust the position of said finger to vary the timing of said interruption of said feed-member's rotation. 75
  15. In a sheet-feeder, a feed-member to advance the sheets and means for lowering and swinging said member rearwardly to retract each sheet before advancing same. 80
  16. In a sheet-feeder, a feed-member intermittently rotatable for lowering and swinging the sheets and means to actuate said member rearwardly while at rest to retract each sheet before rotating same to advance the sheet. 85
  17. In a sheet-feeder, a feed-member intermittently rotatable to advance the sheets and means for lowering said member while at rest to pick up the sheet, said member when lowered and swung rearwardly also retracting said sheet before said member advances same. 90
  18. In a sheet-feeder, a suction feed-member intermittently rotatable in one direction to advance the sheets and means to swing said member rearwardly to retract the sheet picked up by said member while at rest be- 95

fore said member is rotated to advance the sheet.

19. In a sheet-feeder, a suction feed-member intermittently rotatable in one direction to advance the sheets, means for preliminarily moving said member rearwardly to 5 retract the sheet picked up by said member

while at rest, and means controlled by the advanced sheet for varying the extent of the sheet-advancing movement of said member 10 in any part of the cycle.
